(57) **CLAIM**

The ornamental design for a hinged radio frequency identification tag reader, as shown and described.

DESCRIPTION

FIG. 1 is a perspective view of a hinged radio frequency identification tag reader showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is another perspective view thereof; and,

FIG. 9 is another perspective view thereof.

The broken line showing the environment is for illustrative purposes only and forms no part of the claimed design.

1 Claim, 6 Drawing Sheets
